Primary Examiner — Rhea Shields(74) *Attorney, Agent, or Firm* — Leydig, Voit & Mayer, Ltd.(57) **CLAIM**

The ornamental design for a filter cartridge for welding respirator, as shown and described.

DESCRIPTION

FIG. 1 is a top, front, right side perspective view of a filter cartridge for welding respirator showing my new design; FIG. 2 is a bottom plan view of the filter cartridge for welding respirator shown in FIG. 1.

FIG. 3 is a top plan view of the filter cartridge for welding respirator shown in FIG. 1;

FIG. 4 is a front elevational view of the filter cartridge for welding respirator shown in FIG. 1;

FIG. 5 is a rear elevational view of the filter cartridge for welding respirator shown in FIG. 1;

FIG. 6 is a left elevational side view of the filter cartridge for welding respirator shown in FIG. 1; and,

FIG. 7 is a right elevational side view of the filter cartridge for welding respirator shown in FIG. 1.

The broken lines shown in the drawings represent portions of the filter cartridge for welding respirator that form no part of the claimed design.
